SILL STEP FOR RAILROAD CARS

Edward T. Doherty, Chicago, Ill., assignor to Apex Railway Products Co., Chicago, Ill., a corporation of Delaware

Application June 15, 1940, Serial No. 340,649

4 Claims. (Cl. 105—443)

This invention relates to improvements in sill steps for railroad cars and it consists of the matters hereinafter described and more particularly pointed out in the appended claims.

The conventional sill step by which trainmen mount and dismount from a railroad car, other than a passenger car, usually consists of a U-shaped iron attached to and depending from the sill of a car, and disposed in a position associated with either the side ladder or end ladder of the car. Trainmen often mount and dismount from a moving car and often ride the car, while it is in motion, by standing upon said step. Under certain weather conditions, ice forms on the step and as the step has such a surface contour that the weight of the trainmen standing on said step will not break the ice therefrom, an indeed hazardous footing is present for the trainmen.

One of the objects of the invention is to provide a sill step for railroad cars, which presents a safe anti-slip footing for trainmen in boarding or dismounting from a car or when standing on said step in riding said car.

Another object of the invention is to provide a sill step of this kind which is self-cleaning so that snow cannot accumulate thereon and one wherein such ice that may form thereon is cracked and broken therefrom, under the weight of the trainmen.

Again, it is an object of the invention to provide a sill step which prevents endwise or sidewise slipping of the foot of the trainmen when swinging from a ladder on the associated end of the car to the step, thereby insuring safety for the trainmen.

Also, it is an object of the invention to provide a sill step which presents a better "feel" to the foot of the trainmen.

Also, it is a further object of the invention to provide a sill step which although it is of simple construction for low cost production, has a safety factor beyond that required in sill steps.

The above mentioned objects of the invention, as well as others, together with the several advantages thereof will more fully appear as the specification proceeds.

In the drawing:

Fig. 1 is a view in side elevation of an end portion of a railway box car to which the improved sill step has been applied;

Fig. 2 is a horizontal sectional view, on an enlarged scale, through the sill step as taken on the line 2—2 of Fig. 1;

Fig. 3 is a vertical sectional view on the scale 55 of Fig. 2 as taken on the line 3—3 of Fig. 2, and

Fig. 4 is a fragmentary perspective view on a further enlarged scale of a corner portion of one of the counterpart members of which the improved sill step is made.

Referring now in detail to that embodiment 5 of the invention illustrated in the drawing: 5 indicates as a whole the body of a railroad box car that includes a side 6, an end 7, a roof 8 and a side sill 9, all arranged in a manner conventional in cars of the kind mentioned. On the end 7 of the car body are vertically spaced rungs 10 constituting one of the "end" ladders for the car. On the side 6 of the car body are vertically spaced rungs 11 constituting one of the "side" ladders for the car.

The side ladder is most often used by the trainmen when boarding a car. However, the end ladder may be used in some instances for this purpose, while either ladder may be used in dismounting from the car.

Fig. 2 the bar portions 17 are shown as joined together by spot welding and which is indicated as at 21. When said bars are so joined together, the portions 17 jointly form the hangers or supporting arms 14 of the step, while the now spaced apart bar portions 16 coact to form the step portion 13 which is of a relative open construction. The bar portions 16 of the step are held in rigid spaced apart relation by spacers 22-22. As best shown in Figs. 2 and 3, each spacer comprises a short piece of relatively flat bar stock of a length substantially corresponding to the spacing between the bar portion 16-16. The bar stock mentioned is wider than it is thick and the pieces thereof forming said spacers are disposed vertically edgewise with their ends engaged against and then welded to the inner faces of the bar portions 16. This welding is best shown at 23 in Fig. 2. When said spaces are so welded in place, the top edges thereof are disposed substantially flush with or slightly below the bottom surface of the gullets 20 of said bar portions 16.

It is preferred that each projection 19 before mentioned be in the form of a truncated triangle 25 so as to have a flat top portion 19a. The contour provided by the projections 19 and the gullets 20 is such that the truncated ends of said projections, while sharp enough to crack or break ice therefrom under the weight of the trainmen 30 standing thereon are not so sharp as to lacerate the hand grabbing thereat. The projections provide ample protection against the foot of the trainmen slipping either longitudinally or transversely as when swinging from an end ladder of the car to the step in dismounting from the car. Also, the use of the spacers 22, prevents the lateral collapse or bending of the bar portions 16 of the step, under the downward and inward pressure exerted by the trainmen when standing on 35 the step and hanging onto one of the rungs of the side ladder in the inclined position the trainmen assume when hand-signalling. Also, the spacers divide the open area of the step into smaller ones of such size that it is impossible for 40 the trainman to stick his foot in between said bars in any maneuver he may go through in boarding or dismounting the car. However, such openings are not of such small size as to permit the building up of an accumulation of snow on 45 the step to close said openings.

From the above, it is apparent that the improved sill step presents a safe and comfortable standing surface for the trainmen regardless of weather conditions.

While in describing the invention, I have referred in detail to the form, arrangement and

construction of the parts involved, the same is to be considered only in the illustrative sense so that I do not wish to be limited thereto except as may be specifically set forth in the appended claims.

I claim as my invention:

1. A sill step or the like for railroad cars embodying therein a relatively open step part including substantially parallel spaced apart bar-like portions, means associated with the top edge 10 of at least one of said bar-like portions for forming an anti-slip tread surface for the step part, end portions of both bar-like portions being formed to engage each other, and means for operatively securing the engaged end portions of 15 said bar-like portions to a part of a railroad car for support thereby.

2. A sill step for a railroad car embodying therein a relatively open step part including substantially parallel spaced apart bar-like portions, 20 means associated with the top edges of said bar-like portions for forming an anti-slip tread surface for said step part, the end parts of said bar-like portions being offset laterally from the mid parts of said bar-like portions and the end parts 25 of both bar-like portions being joined together, and means extending upwardly from both ends of the step part and adapted for attachment to a part of a railroad car so as to be pendently supported therefrom.

3. A sill step for a railroad car embodying therein a relatively open step part including substantially parallel spaced apart bar-like portions, means associated with the top edges of said bar-like portions for forming an anti-slip tread surface for said step part, the end parts of said bar-like portions being offset laterally from the mid parts of said bar-like portions and the end portions of both bar-like portions being joined together, each bar-like portion having an upward 40 extension at least at one end, said extensions being adapted for attachment to a railroad car so as to be pendently supported therefrom.

4. A sill step for a railroad car and made from two counterpart U-shaped members, each including a horizontal portion and upwardly extending end portions, which are disposed in a plane offset laterally from the plane of said horizontal portion, the upwardly extending end portions of one U-shaped member being fixed to the 50 like end portions of the other U-shaped member, said horizontal portions of both U-shaped members being formed to provide anti-slip tread surfaces, and means extending between said horizontal portions for spacing them apart.

EDWARD T. DOHERTY. 55
